UNITED STATES PATENT OFFICE.

REUBEN A. MITCHELL AND FRANK A. EMERICK, OF OIL CITY, PENNSYLVANIA.

ELECTRIC HEAT-ENGINE.

1,063,824.

Specification of Letters Patent.

Patented June 3, 1913.

Application filed July 5, 1910. Serial No. 570,417.

To all whom it may concern:

Be it known that we, REUBEN A. MITCHELL and FRANK A. EMERICK, citizens of the United States, residing at Oil City, in the county of Venango and State of Pennsylvania, have invented certain new and useful Improvements in Electric Heat-Engines; and we do hereby declare the following to be a full, clear, and exact description of the invention, such as will enable others skilled in the art to which it appertains to make and use the same.

This invention relates to improvements in engines, and more particularly to engines which use expansive force of gaseous matter as the motive force.

The object in view is the provision of means for intermittently heating air which is in free communication with a piston for causing the expansion of the air which will react on the piston for moving the same.

A further object in view is the arrangement in an engine of means for using air over and over again from the original pressure by heating a part of the air and expanding the same, and then exhausting the expanded air into the unheated air at predetermined cycles.

A still further object of the invention is the arrangement in an engine having a cylinder and a piston, of an air chamber in proximity thereto and a cooling chamber around the air chamber together with an electrical heating devise arranged to heat the air in the cylinder for expanding the same, after which it is exhausted into the compression chamber where the same is cooled.

With these and further objects in view, the invention comprises certain novel constructions, combinations and arrangements of parts as will be hereinafter fully described and claimed.

In the accompanying drawings:—Figure 1 is a longitudinal, vertical section through an embodiment of the invention. Fig. 2 is a cross sectional view through Fig. 1 on the line 2—2. Fig. 3 is a section through Fig. 2 on the line 3—3. Fig. 4 is a detail, fragmentary view of the means for connecting the regulator with the drive shaft.

Referring to the accompanying drawings, 1 indicates a cylinder which may be of any desired type for accommodating a relatively long, hollow, reciprocating piston 2. Piston 2 is connected with the piston rod 3 from

which power is conveyed to power shaft 4 through any usual or preferred means. Surrounding cylinder 1 is an air chamber 5 which is in turn surrounded by a water chamber 6. It will, of course, be understood that any other desired cooling medium other than water may be used for reducing the air in chamber 5 to the desired temperature. Chamber 5 is initially supplied with compressed air in any preferred manner, as, for instance, through a valved supply pipe, such as is illustrated in Fig. 1. An exhaust port 7 is formed in cylinder 1 approximately midway of the length thereof communicating with chamber 5 so that when the piston is at the rear end of its stroke the air in the cylinder 1 and chamber 5, may assume an equilibrium. A pipe or port 8 leads from one end of cylinder 1 to the other end thereof, and check valves 9 and 9' are provided therein for controlling admission of air from the rear end of the cylinder to the front end thereof and from chamber 5 to the rear end of the cylinder.

A heating chamber 11 is arranged just beyond the front end of cylinder 1 and separated therefrom by a pair of spaced walls apertured as at 10 for affording communication with cylinder 1. A valve or gate 12 is provided for being moved across the openings or port 10 by the actuation of a controlling screw 13 for at times cutting off communication between cylinder 1 and chamber 11. Arranged in heating chamber 11 are electrodes 14 and 15 between which a spark is established when it is desired to heat the air in chamber 11. These electrodes may be made of any desired material and are removably secured in sockets 16 and 17 so as to be easily replaced. Socket 17 is mounted upon a rock shaft 18 which has secured thereto a crank 19 geared to shaft 4 for oscillating the crank for shifting the electrode 15 for making and breaking the circuit, whereby a spark is produced each time the electrode 15 contacts with and separates from electrode 14. A packing box 20 is provided for rock shaft 18 so as to prevent the escape of pressure. The actuating gear of crank 19 is timed to cause a spark between electrodes 14 and 15 just as piston 2 arrives at the extreme of its forward movement.

Socket 16 of electrode 14 is connected with a longitudinally movable shaft 21, which is also provided with a packing box

22. Pivotally engaging the outer end of shaft 21 is a link 23 which is in turn pivotally connected to a walking beam 24. Beam 24 is pivotally connected with a link 25 which pivotally engages a lever 26, which lever is fulcrumed upon a bearing 26' and is provided with a contact member or projection 27 at the end opposite link 25 for engaging the lower end 28 of a governor 29.
- 10 5 The governor 29 is connected by a belt 30 in any usual or preferred manner with shaft 4. The governor 29 is designed to operate in the usual manner for raising and lowering the end of lever 26 connected therewith.
- 15 10 As will be evident, in instances of appreciable variations in speed, shaft 21 will thus be shifted toward or away from electrode 15 according to the variation whether a slowing down or a speeding up, and consequently varying the distance between electrode 14 and electrode 15, for varying the resultant sparking, whereby the speed of the engine is regulated. Increased speed of the piston will cause the electrodes to approach and thus shorten the arc therebetween, proportionately reducing the intensity of the heat from such arc, and this approach may be carried to the extent of actual contact of the electrodes, upon which the 20 15 arc is totally discontinued, thus allowing the air to cool until the speed decreases and the electrodes are again moved apart, and thus reestablish the arc with a resultant rise in temperature.
- 25 20 The cycles of operation may readily be followed from the foregoing, and may be traced as follows: Piston 2 being at the front end of the cylinder 1, a spark is produced between electrodes 14 and 15 by the turning 30 25 on of the electrical current by means not illustrated, the circuit of the current being of any preferred arrangement so as to include said electrodes. Instantly upon the production of a spark, the heat acting to expand the air in chamber 11, causes, through the action of such expansion, piston 2 to travel rearwardly until its front end passes port 7, said port having been previously covered after the starting of the piston, and at 35 30 this point the hot compressed air expands through port 7 into cooling chamber 5, immediately following which the charge of cool air at the rear of the piston is admitted past valve 9 into the front end of the cylinder, and piston 2 starts forward closing port 7 and seating valve 9. The advance of the piston compresses the fresh cool charge into chamber 11 until the piston arrives at the foremost point of its travel, 40 45 whereupon electrodes 14 and 15 emit a spark which heats the formerly cool air charge and, expanding the same, effects a repetition of the cycles stated. Obviously as piston 2 advances each time a fresh charge of cool 50 55 air is admitted past valve 9 in the rear of

the piston, which charge is more or less compressed by the return of the piston and thus seeks admission to the front end of the cylinder and rapidly enters the same immediately after the hot charge has exhausted through port 7. Obviously, fluid medium other than air may be utilized, and the air or other medium (which for convenience will be called "air" in the appended claims) may be more or less compressed when in its most condensed or cooled state, and we find a higher degree of efficiency is obtained when the air is somewhat compressed when initially introduced to the cylinder and chambers.

70 75 It will be observed that the device discloses the application of a new principle or a combination of principles hitherto unused, whereby a reservoir of compressed air remaining stationary is utilized without any 80 85 exhaust whatever into or against atmospheric pressure or into any vacuum, but exhausts only into the reservoir itself, a power being derived from the expansion of the compressed air by heating successively 90 and cooling successively.

95 100 What we claim is:

1. In combination, a cylinder, a piston arranged therein, the cylinder being formed with a plurality of ports, an air reservoir surrounding said cylinder and communicating therewith by one of said ports, a heating chamber arranged in proximity to said cylinder and communicating therewith through one of said ports, and means for intermittently heating air in said heating chamber and expanding the same into said cylinder.

105 110 115 2. In combination, a cylinder, a reciprocating piston arranged therein, an air chamber surrounding said cylinder and communicating therewith substantially centrally thereof, a cooling chamber surrounding said air chamber, a heating chamber in communication with one end of said cylinder, and electrical heating means for heating the air in said heating chamber, and means for intermittently causing said electrical heating means to heat the air in said heating chamber.

120 125 130 3. In combination, a cylinder, a piston arranged in said cylinder, an air chamber surrounding said cylinder and in communication therewith, a cooling chamber surrounding said air chamber, a heating chamber, a pair of electrodes arranged in said heating chamber, means for intermittently causing said electrodes to heat the air in said heating chamber, and regulating means for varying the distance between said electrodes for controlling the heat generated thereby.

4. In combination, a cylinder, a piston adapted to reciprocate in said cylinder, an air chamber surrounding said cylinder and in communication therewith, a plurality of 130

valves adapted to permit the establishing of an equilibrium in said cylinder on both sides of said piston when the piston is at one end of said cylinder, means for heating the air in one end of said cylinder for expanding the same, and a cooling chamber surrounding said air chamber.

5. In combination, a cylinder, a reciprocating piston arranged therein, an air chamber surrounding said cylinder and communicating therewith substantially centrally thereof, a cooling chamber surrounding said air chamber, a heating chamber in communication with one end of said cylinder, means 10 for creating an arc for heating air in said heating chamber, and a governor actuated by the piston and connected for varying the length of said arc relative to the speed of the piston.

6. In combination, a cylinder, a piston arranged therein, the cylinder being provided with a plurality of ports, an air reservoir surrounding said cylinder and communicating therewith by one of said ports, a heating chamber arranged in proximity to said cylinder and communicating therewith through one of said ports, means for intermittently heating air in said heating chamber and expanding the same into said cylinder, and a cooling jacket surrounding said air reservoir. 20 25 30

In testimony whereof we affix our signatures in presence of two witnesses.
